SYRINGE

Newell D. Hartley, Devon, Conn.

Application October 10, 1958, Serial No. 766,587

7 Claims. (Cl. 128—234)

The present invention relates to a syringe of the type having a hollow tube or barrel provided with a restricted orifice at one end and with its other end being open to admit a piston. The piston is movable within the tube to provide pressure for ejecting fluids therefrom or a vacuum for introducing fluid through the orifice into the tube.

At present such syringes are generally manufactured with a glass barrel and a glass piston, the outer walls of the piston and inner walls of the barrel are ground to form a sealing fit therebetween, and thus in effect each piston and barrel are mated preventing any intermixing of the two elements. While these syringes function, such structure is inherently expensive in view of the necessity of forming the sealing fit. In addition, such syringes suffer from the inherent common characteristic of glass, namely being fragile and tending to break even with slight blows.

An object of the present invention is to provide a syringe which is economical to manufacture and reliable in use without requiring a sealing fit to be formed between the barrel and the outer walls of the piston.

Another object of the present invention is to provide a syringe of the above type which has a fragile barrel and a relatively rigid, non-fragile piston and for the minimization of possible breakage of the barrel caused by the piston moving and hitting the barrel.

A further object of the present invention is to enable a barrel of a syringe to have relatively large deviations in dimensions of its inner wall surfaces and to provide a piston with resilient portions which effect a seal therewith irrespective of the deviations, thereby enabling a more economical barrel to be used.

In carrying out the present invention, there is provided a barrel of the type having a restricted orifice at one end, an open end at the other and a piston operable within the barrel. The cross-sectional shape of the inner working portion of the barrel is substantially constant throughout its length, though it may vary within relatively large tolerances for a syringe barrel. The piston has a cross-sectional shape which is smaller than the smallest cross-section area of the barrel, and if desired may be many times smaller, it not being essential to the present invention that the working length of the barrel have a constant-shaped or size cross section. Thus a limited amount of movement between the piston and the barrel in a direction perpendicular to the axis of the piston occurs.

In order to form the seal, the piston is provided with a groove adjacent its working end (with the other end being formed to provide a handle) and within this groove there is positioned a ring of resilient material, such as rubber. The normal, outside periphery of the ring is larger than the largest cross-sectional shape of the working length of the barrel and hence upon insertion of the piston within the barrel the ring is compressed and forms a seal between the piston and the barrel.

When the barrel is formed of fragile material, such as glass, and the piston is formed of rigid material, such as

metal, the ring forms, in addition to a seal, a resilient bumper between the two elements at the place where it is positioned on the piston, thereby preventing the piston from damaging the barrel. However, when the piston is 5 completely or almost completely within the barrel, then the handle end of the working portion of the piston has room to move and has a tendency upon such jarring of the syringe to hit the barrel and cause breakage thereof. This is obviated according to the present invention by 10 forming an annular groove adjacent the handle end of the working portion of the piston and positioning within this groove a ring of resilient material similar to that used at the working end of the piston. This ring serves as a resilient bumper between the barrel and the piston to cushion movement of the piston and prevent it from shattering the fragile barrel.

The second resilient ring in addition to achieving the above object further aids in preventing breakage of the barrel by the piston during use. The second ring also 20 forms a seal with the barrel; however, this seal only occurs when the piston is almost completely within the barrel. This is decidedly advantageous since, as the piston moves into the barrel and approaches its final position, the second ring causes an additional force resisting movement of the piston which tends to prevent the working end of the piston from hitting the restricted end of the barrel with sufficient force to break the barrel.

While it has been found that one resilient ring is sufficient to form the seal, a third resilient ring may be positioned between the rings at each end of the working portion of the piston if this portion is relatively long or if there is too much play between the piston and the barrel at intermediate positions of the barrel.

Other features and advantages will hereinafter appear. In the drawings:

Figure 1 is a sectional view taken along an axial section of a syringe constructed according to the present invention.

Fig. 2 is a view of the barrel and its resilient members.

Fig. 3 is a view taken on the line 3—3 of Fig. 1 in the direction of the arrows.

Referring to the drawing, the syringe of the present invention generally indicated by the reference numeral 10 consists of a hollow barrel 11 and a piston 12 operable therein. The barrel 11 at one end has inturned portions 45 13 defining a reduced orifice 14 leading outwardly through a neck 15. A bead 16 is formed on the exterior of the neck 15 to increase the sealing engagement thereof with an end portion of a pliable hose 17.

The other end of the barrel is open as at 18 and between the opening 18 and the portions 13 the barrel has a substantially circular cross section as indicated in Fig. 3, though, of course, it may be oval if desired. The inner walls of the barrel 11 between the opening 18 and 55 the inturned portion 13 is referred to as the working portion of the barrel since the piston works within this portion. The cross-sectional shape of the working portion is substantially identical throughout its length; however, it may have relatively large tolerances (for a syringe barrel) to enable a more economical barrel to be used. Flanges 19 are formed adjacent the opening 18 to enable the user to grasp the barrel.

The piston 12, as shown in Fig. 2, has a working or operating portion which is specifically shown as having a substantially cylindrical length for a distance which is approximately equal to the working length of the barrel. A handle 20 is formed at one end of the working portion of the barrel and may have any shape desired; however, in the disclosed embodiment, it is merely a circular knob connected to the working portion.

A radial peripheral groove 21 is formed in the piston adjacent the working end of the piston and a similar

groove 22 is formed adjacent the other end of the working portion of the piston nearest the handle 20. These grooves (21 and 22) are of sufficient depth and width to hold and maintain in place rings 23 and 24 of resilient material.

The rings 23 and 24, as specifically disclosed, are rubber O-rings and have a normal peripheral diameter which is larger than the largest diameter of the working portion of the barrel, thereby causing, when the rings engage the barrel, a compression of the rings. This compression causes a seal between the rings and the barrel, which in the case of the ring nearest the working end of the piston is sufficient to create a seal between the barrel and the piston even with the relatively large tolerances in the cross-sectional shape of the barrel. It will thus be appreciated that only one ring (23) is necessary to create the sealing fit.

In the disclosed embodiment of the invention the barrel 11 is formed of fragile material, glass, and the piston is formed of anodized aluminum, and hence is a rigid, non-resilient material. With only a single O-ring adjacent the working end of the piston and with the piston completely within the barrel, the other end of the piston adjacent the opening 18 can move laterally. This movement or play is such that in the case when the syringe is abruptly moved, it may cause breakage of the barrel by the piston hitting it.

According to the present invention, however, the resilient ring 24 serves as a bumper between the piston and the barrel and obviates breakage caused by lateral movement of the piston.

When in use, as the piston is introduced and forced down the barrel towards the neck portion 15, the only resistive force is caused by engagement between the ring 23 and the barrel (excluding the effect of any fluid pressures), and hence there is a tendency for the piston to maintain its speed and to hit the portion 13 with a force which may be great enough to break the portion 13. The ring 24 positioned on the piston to engage the inner walls of the barrels prior to the piston being completely within the barrel obviates this condition by increasing the resistive force to movement of the piston. Thus this second ring 24 tends to prevent the piston from hitting the end of the barrel with a force sufficient to break it.

In syringes which have a relatively long working length and also relatively long operating lengths of the piston, it is at times desirable to add a third resilient member which may be an O-ring 25 positioned between the other two, preferably centered therebetween to limit play of the piston during and at its intermediate position. This third O-ring which is similar to the rings 23 and 24 is positioned and maintained in a groove 26, similar to the grooves 21 and 22, and operates in the same manner as the second O-ring 24 to perform the same functions.

It will accordingly be appreciated that there has been disclosed a syringe that is relatively economical to manufacture, which is reliable in use over an extended period and in which the tendency of a fragile barrel to be broken by a rigid piston is substantially minimized.

Variations and modifications may be made within the scope of the claims and portions of the improvements may be used without others.

I claim:

1. A syringe comprising a hollow barrel having a restricted orifice formed in one end and the other end being open and defining an opening having a cross-sectional shape, said barrel having an operating length with its inner walls defining a cross-sectional shape throughout the length which is substantially identical to the cross-sectional shape of the opening; a piston formed of relatively rigid material having an operating portion and a handle portion extending from one end of the operating portion, the length of the operating portion being at least as long as the length of the hollow operating length of the barrel, a radial peripheral groove formed in the piston adjacent one end of the operating portion, a second radial peripheral groove formed in the operating portion of the piston and spaced from the first groove a distance slightly less than the operating length of the barrel, and a ring of resilient material positioned and maintained in each groove, the periphery of the rings being larger than the periphery of the opening of the barrel and being compressed by the operating length of the barrel upon engagement therewith as the operating length of the piston is inserted into the barrel to cause a seal therebetween.

2. A syringe comprising a barrel having a hollow cylindrical operating length provided with a restricted orifice formed in one end and the other end being open and defining a substantially circular opening, a piston formed of relatively rigid material to have an operating portion and a handle portion, the operating portion being at least as long as the length of the hollow operating length of the barrel, a radial peripheral groove formed in the piston adjacent one end of the operating portion, a second radial peripheral groove formed in the operating portion of the piston and spaced from the first groove a distance slightly less than the operating length of the barrel, and a ring of resilient material positioned and maintained in each groove, the diameter of the rings being larger than the diameter of the opening and being compressed by the operating length of the barrel upon engagement therewith as the operating length of the piston is inserted into the barrel to cause a seal therebetween.

3. A syringe comprising a hollow barrel having a restricted orifice formed in one end and the other end being open and defining an opening having a cross-sectional shape, said barrel having an operating length with its inner walls defining a cross-sectional shape throughout the length which is substantially identical to the cross-sectional shape of the opening; a piston formed of relatively rigid material having an operating portion and a handle portion extending from one end of the operating portion, the length of the operating portion being at least as long as the operating length of the barrel, a peripheral ring groove formed in the piston adjacent one end of the operating portion, a second radial peripheral groove formed in the operating portion of the piston and spaced from the first groove a distance slightly less than the operating length of the barrel, and a ring of resilient material positioned and maintained in each groove, the diameter of the rings being larger than the diameter of the opening and being compressed by the operating length of the barrel upon engagement therewith as the operating length of the piston is inserted into the barrel to cause a seal therebetween.

4. A syringe comprising a barrel having a hollow cylindrical operating length provided with a restricted orifice formed in one end and the other end being open and defining a substantially circular opening, a piston formed of relatively rigid material to have an operating portion and a handle portion, the operating portion being at least as long as the length of the hollow operating length of the barrel, a radial peripheral groove formed in the piston adjacent one end of the operating portion, a second radial peripheral groove formed in the operating portion of the piston and spaced from the first groove a distance slightly less than the operating length of the barrel, a third peripheral ring groove formed in the operating portion of the piston between the other two grooves, and a ring of resilient material positioned and maintained in each groove, the periphery of the rings being larger than the periphery of the opening of the barrel and being compressed by the operating length of the barrel upon engagement therewith as the operating length of the piston is inserted into the barrel to cause a seal therebetween.

5. A syringe comprising a barrel having a hollow cylindrical operating length provided with a restricted orifice formed in one end and the other end being open and defining a substantially circular opening, a piston formed of relatively rigid material to have an operating portion and a handle portion, the operating portion being at least as long as the length of the hollow operating length of the barrel, a radial peripheral groove formed in the piston adjacent one end of the operating portion, a second radial peripheral groove formed in the operating portion of the piston and spaced from the first groove a distance slightly less than the operating length of the barrel, a third radial peripheral groove formed in the operating portion of the piston between the other two grooves, and a ring of resilient material positioned and maintained in each groove, the diameter of the rings being larger than the diameter of the opening and being compressed by the operating length of the barrel upon engagement therewith as the operating length of the piston is inserted into the barrel to cause a seal therebetween.

5. The invention as defined in claim 1 in which the rings are toroidal having a circular cross-section and are formed of rubber.

6. The invention as defined in claim 1 in which the barrel is formed of glass and the piston is formed from 5 aluminum.

7. The invention as defined in claim 6 in which the

rings are toroidal having a circular cross-section and are formed of rubber.
